(57) **CLAIM**

The ornamental design for a scalp measurement device, as shown and described.

DESCRIPTION

FIG. 1 is a perspective view of the scalp measurement device.

FIG. 2 is a front view thereof.

FIG. 3 is a rear view thereof.

FIG. 4 is a left side view thereof.

FIG. 5 is a right side view thereof.

FIG. 6 is a top view thereof; and,

FIG. 7 is a bottom view thereof.

In FIG. 1, the thin lines are to indicate the curved surface. The broken lines shown in the drawings represent portions of the scalp measurement device that form no part of the claimed design.
